JOHN W. KILLINGSWORTH, OF ATLANTA, GEORGIA.

BANDING MACHINE.

Application filed March 21, 1927. Serial No. 177,178.

This invention relates to a banding machine designed primarily for use in the banding of locomotive springs of the leaf laminated type, but it is to be understood that 5 a machine, in accordance with this invention can be employed for any purposes for which it is found applicable, and the invention has for its object to provide, in a manner as hereinafter set forth, a machine of the 10 class referred to for expeditiously and efficiently applying bands or clips to the familiar elliptic, either full or half, leaf or laminated spring for securely binding together the leaves or laminations thereof.

15 Further objects of the invention are to provide, in a manner as hereinafter set forth, a banding machine for the purpose referred to, which is simple in its construction and arrangement, strong, durable, compact, 20 thoroughly efficient and convenient in its use, readily assembled, and comparatively inexpensive to set up.

With the foregoing and other objects in view the invention consists of the novel construction, combination and arrangement of parts as hereinafter more specifically described and illustrated in the accompanying drawings, wherein is shown an embodiment of the invention, but it is to be understood 25 that changes, variations and modifications can be resorted to which fall within the scope of the claims hereunto appended.

In the drawings wherein like reference characters denote corresponding parts 30 throughout the several views:

Figure 1 is a side elevation of a banding machine in accordance with this invention.

Figure 2 is a top plan view of a suspension structure for the operating elements of the 40 machine and with said structure partly shown in section.

Figure 3 is a longitudinal sectional view of the suspension structure and further illustrating the means for supporting it.

45 Figure 4 is a section on line 4—4 Figure 1.

Figure 5 is a section on line 5—5 Figure 1 and partly in section.

Figure 6 is a detail illustrating the combined holder and presser element.

50 Figure 7 is a fragmentary view in section of the machine and illustrating the combined band holder and presser element and the upsetting element in operative position with respect to the band or clip, the latter being 55 illustrated as secured to the spring.

Referring to the drawings in detail a

banding machine, in accordance with this invention, includes a suspension element or structure, referred to generally by the reference character 8 and consisting of a longitudinally disposed body portion 9 of appropriate length, height and thickness, and which has its rear end downturned as at 10 and merging into a yoke-shaped hanger 11 having the arms thereof indicated at 12, 13. 60 Each arm is formed with an opening 14 through which extends a gudgeon 15, carried by a plate 16 positioned against the outer face of the arm and secured therewith by holdfast devices 17. The outer face of each 65 of the arms of the yoke 11 is formed with a vertically disposed, flat rectangular offset or enlargement 17' having apertures 18. Extending from each enlargement 17' to the body portion 9 is a reinforcing web 19. The 70 body portion 9, intermediate its ends is formed with an upstanding arm 20 having the upper end thereof bifurcated, as at 21 and provided with aligning openings 22. The base of the bifurcation at the upper end 75 of the arm 20 is indicated at 23 and is of arcuate contour. Depending from the body portion 9, at a point between the arm 20 and the yoke 11, is a curved extension 24 which terminates in a yoke 25 provided with 80 a pair of arms 26, 27 and each of which is formed with an opening 28 for the passage of a gudgeon carried by a plate 29, the latter being secured to its associated arm by holdfast devices 30. The outer faces of the arms 85 26, 27 are reinforced by webs 31, which extend to and upon the extension 24. The body portion 9 between the arm 20 and the forward end thereof is formed with an opening or passage 32 which extends from the top 90 to the bottom thereof and is provided with inclined walls 33, 34, the former extending at a greater inclination than the latter and which is the rear wall of the opening. The body portion 9 in proximity to the top thereof is formed with a pair of openings 35 arranged in proximity to the walls 34 and which communicate with the opening or 95 passage 32.

The suspension element 8 is supported at 100 its front and at its rear by standards and the standards employed at the front thereof are indicated at 36, and those at the rear at 37. The standards 36 are connected at their upper ends by holdfast devices 38 to the forward end of the body portion 9 and the standards 37 are connected at their upper 110

ends with the element 8, by holdfast devices 39 which extend to the enlargements 17' formed on the arms 12 and 13.

The gudgeons secured to the arms 12, 13 of the yoke 11, are provided for suspending a fluid pressure actuating device 40 for a piston rod 41', the latter projects upwardly from the device 40 and said device is vertically disposed. The arms 26, 27 of the yoke 11 overlap a fluid pressure actuating device 41 for a piston rod 42. The gudgeons carried by the arms 26, 27 support the fluid pressure actuating device 41, at an inclination and below the device 40. The device 41 is arranged forwardly with respect to the lower portion of the device 40 and depends at a downward inclination. Mounted in the bifurcated upper end of the arm 20 at a point between its vertical median and its forward end is a lever arm 43, which is pivotally connected to the arm 20, as at 44. The lever arm 43 projects slightly forward of the arm 20. The rear end of the lever 43 is pivotally connected as at 45, to the upper end of the piston rod 41'. The forward end of the lever arm 43 has pivotally connected therewith, as at 46 a depending combined holder and presser head or element 47. Pivotally connected to the outer end of the piston 42, as at 48, is an upstanding lever arm 49, which extends through the opening 32 and is pivoted with the body portion 9 as at 50. The pivot 50 is arranged between the transverse median and upper end of the arm 49 and further at a point between its longitudinal median and its forward edge. The pivot 50 is eccentrically disposed with respect to the opening 32, that is to say it is arranged at a point between the vertical median and the forward wall of the opening 32 and further above the longitudinal center of the body portion 9. The lever arm 49 extends a short distance above the body portion 9 and that part of the forward edge of said arm 49, above and below the pivot 50 inclines rearwardly throughout. The upper end of the lever arm 49 carries a pivot 53 which projects from each side face thereof and connected to the projecting ends of the pivot 53 are links 54 having their rear ends pivotally connected as at 55, to an upsetting head or element 56, which is normally arranged below the element 47 and slides upon the upper face of the body portion 9 forwardly with respect to the arm 20. When active the element 56 moves towards the arm 20 and the element 47 moves towards that part of the body portion 9 which is arranged forwardly of the arm 20. That part of the body portion 9 between the arm 20 and the rear wall of the opening 32 provides a seat or anvil 57 for the band or clip 58 when the latter is mounted on the spring 59, see Figure 7.

66 The head or element 47 compresses the

sides of the clip or band against the spring 59 and the element or head 56 upsets the free ends of the band or clip and further compresses the inner end of the clip or band when it is in the position shown in Figure 7. 70

The devices 40, 41 are provided for rocking the lever arms on their pivots for the purpose of shifting the elements 47 and 56 to active position with respect to the clip or band 58 for the purpose of securing it to the spring 59 to tightly bind the leaves or laminations of the spring together. Any suitable means is employed for controlling the supply of fluid pressure to the devices 40 and 41. Preferably the band is forged to 80 the spring. It will be understood, of course, that any suitable clamping means may be employed to hold the leaves or laminations of the springs together pending the closing 85 of the clip or band or pending the upsetting or forging of the clip or band in position to tightly bind the leaves or laminations of the spring together. The spring with the clip or band is positioned on the part 57 of the suspension element 8, and then the devices 40 and 41 are thrown into operation which provide for the elements 47 and 56 to engage the band to secure it in position on the spring and after such action has taken place the elements 40 and 41 are controlled 90 in a manner to release the lever arms 43 and 49 so that they will assume their normal positions as shown in Figure 1. When the devices 40 and 41' are operated the piston 41' is moved upwardly and the piston 42 forwardly and when the piston 41 moves upwardly the lever arm 43 is carried therewith, that is the rear end thereof, which lowers the forward end of the lever carrying the element 47 therewith. When the piston rod 42 moves forwardly the lever arm 49 is rocked on its pivot in a direction whereby the lower end of the arm 49 will move forwardly, which swings the upper end of the arm rearwardly and causes the element 56 to shift 100 to active position. 105

110 It is thought the many advantages of a banding machine, in accordance with this invention can be readily understood, and although the preferred embodiment of the invention is as illustrated and described, yet it is to be understood that changes in the details of construction can be had which will fall within the scope of the invention as claimed. 115

120 What I claim is:

1. A machine for securing a band in position to bind the leaves of a spring together comprising a suspension structure for supporting the band in position to be acted upon, an upper lever disposed longitudinally with respect to and eccentrically pivoted to said structure above the point of supporting the band, a lower lever disposed at an upstanding position with respect to and eccen- 125 130

trically pivoted to said structure and further arranged forwardly of the upper lever, a combined holding and presser element pivotally carried by the forward end of the upper lever, an upsetting element pivotally carried by the upper end of the lower lever and sliding on said structure, and means supported from said structure and connected to the rear end of the upper lever and lower end of the lower lever for actuating said levers to shift said elements simultaneously at right angles to each other to secure the band to the spring.

2. A machine for securing a band to a leaf spring to tightly bind the leaves of the latter together comprising a supporting structure having a part thereof constituting a seat for the band to be operated upon, an upper lever arranged above said part and eccentrically pivoted to said structure, a lower lever arranged forwardly of said part and eccentrically pivoted to said structure, a combined holding and presser element pivotally carried by one end of the upper lever, an upsetting element pivotally carried by said lower lever and sliding on said structure, and means supported from said structure and connected to said levers for operating them to shift said elements in right angularly disposed paths simultaneously for engagement with said band to secure it to the spring.

3. A machine for securing a band to a leaf spring to tightly bind the leaves of the latter together comprising a supporting structure including a part to provide a seat for the band to be operated upon and further including a pair of angularly disposed yokes and an upstanding arm arranged rearwardly of said part, an upper lever pivotally connected in proximity to its forward end to said arm, a lower lever arranged forwardly of the

upper lever, extending upwardly through said structure and pivotally connected in proximity to its upper end to said structure, 45 said lever depending from said structure, band securing elements pivotally carried by the forward end of the upper lever and upper end of the lower lever and travelling in paths at right angles to each other, and 50 fluid pressure actuating devices suspended by said yokes and pivotally connected to the rear end of the upper lever and the lower end of the lower lever and adapted when operated to provide for the shifting of said 55 levers to cause said elements to travel in right angularly disposed paths to engage said band for securing it to a spring.

4. In a machine for the purpose set forth a supporting structure provided at its top 60 with a vertically disposed arm, said structure having that portion of its top forwardly of the arm providing a seat, said structure further including a rearwardly extending and a depending yoke both arranged rearwardly with respect to said arm, an upper lever eccentrically pivoted to said arm, a lower lever extending upwardly through the forward part of said structure and eccentrically pivoted thereto, a pair of band securing elements, one pivoted to the forward end of and depending from the upper lever and the other pivotally connected to the upper end of the lower lever and sliding on 70 said seat, a fluid pressure operated means 75 supported by said rear yoke and pivotally connected to the rear end of the upper lever, and a fluid pressure operated means supported by said depending yoke and pivotally connected to the lower end of the lower 80 lever.

In testimony whereof, I affix my signature hereto.

JOHN W. KILLINGSWORTH.
